MEANS FOR BALANCED DISPATCHING OF
ODD AND EVEN NUMBERS OF ELEVATOR
CARSWalter A. Nikazy, Toledo, Ohio, assignor to
Haughton Elevator Company, Toledo, Ohio, a
corporation of Ohio

Application October 19, 1951, Serial No. 252,102

11 Claims. (Cl. 177—336)

1

This invention relates to elevator control systems and particularly to means for maintaining a balanced relationship between the cars of a bank of elevators serving down traffic and the cars serving up traffic.

When traffic is approximately equal in both directions, regular elevator service to all floors is best provided by dispatching the cars at regular intervals from each of the terminals of the bank of elevators. When an odd number of cars, such as three or five, is in operation the balance between the cars devoted to up traffic and the cars devoted to down traffic is attained by dispatching cars alternately from the upper and lower terminals. When an even number of cars, such as two or four, is in operation the balance between the cars devoted to up traffic and the cars devoted to down traffic is attained by dispatching a car from the upper terminal simultaneously with each dispatch of a car from the lower terminal.

In a typical control system, such for example, as that illustrated and described in United States Patent No. 1,966,071, dated July 10, 1934, a mechanical or electric timing device is employed to space the dispatch signals at equal intervals and to keep the dispatch signals to the lower and upper terminals in step with each other. At the end of each interval the timing device closes two contacts, the first of which is in a circuit that sends dispatch signals to the lower terminal, the second of which can be switched into a circuit that sends dispatch signals to the upper terminal. At the midpoint of each interval the timing device closes a third contact which can be switched into a circuit that dispatches signals to the upper terminal. The switching mechanism is so arranged that manipulating the mechanism to switch in the third contact will switch out the second contact, and vice versa.

Apparatus such as that so far described serves its purpose if the human elevator starter always switches from alternate lower and upper terminal dispatching to simultaneous lower and upper terminal dispatching whenever the number of cars in operation is changed from odd to even, and always switches back to alternate dispatching whenever the number of cars is changed back to odd. However, if, as often happens, the starter forgets or neglects, when the number of cars is changed, to switch from alternate dispatching to simultaneous dispatching or to switch back to alternate dispatching, the service becomes irregular.

It is an object of this invention to provide means for automatically causing dispatch signals to be given alternately to lower and upper termi-

2

nals at regular intervals whenever an odd number of elevators of a bank is in operation, and for automatically causing dispatching signals to be given simultaneously to both terminals at regular intervals whenever an even number of elevators is in operation.

Other objects will be apparent from the following description illustrated by the accompanying drawing which is a diagram of apparatus embodying the instant invention, the apparatus being diagrammed in condition to send dispatch signals alternately to the lower and upper terminals of a bank of five elevators when all five of the elevators are in operation.

15 Any suitable type of timing device may be employed with the apparatus of the instant invention. For simplicity of illustration the drawing shows a motor 1 with reduction gearing 2 which turns a shaft 3 upon which are mounted contact

20 closing cams 4, 5 and 6.

The cam 4 closes a contact 7 at each revolution of the shaft 3 thus completing a circuit through a lower terminal scheduling relay 8, which may be of any desired form and which, therefore, is shown by block diagramming. When the circuit through the relay 8 is completed by the closing of the contact 7 a dispatch signal is sent in the well-known manner to the lower terminal of the bank of elevators. Thus dispatch signals are flashed or sounded at the lower terminal at regular intervals, one for each revolution of the shaft 3.

25 The cam 5 closes a contact 9 simultaneously with the closing of the contact 7 at each revolution of the shaft 3. Closing of the contact 9 does not, however, complete a circuit as long as another contact 10 of the circuit remains open.

The cam 6 closes a contact 11 at each revolution of the shaft, the contact 11 being closed half a revolution after the closing of the contact 7. The contacts 7 and 11 thus are closed alternately. In series with the contact 11 is a contact 12 which when closed permits completion of a circuit through an upper terminal scheduling relay 13 whenever the contact 11 is closed. The relay 13 is similar to the relay 8 and likewise is shown by block diagramming. When the circuit through the relay 13 is completed by the closing of the contact 11, a dispatch signal is sent in the well-known manner to the upper terminal of the bank of elevators. Thus, when the contact 12 is closed and the contact 10 is opened, dispatch signals are sent alternately to the lower and upper terminals, one signal to each terminal during each revolution of the shaft 3.

30 35 40 45 50 55 55 The contacts 10 and 12 are connected to a

relay 14, which when activated opens the contact 10 and closes the contact 12. The relay 14 is energized by a circuit which is completed whenever the number of cars in operation is odd, and is broken whenever the number of cars in operation is even.

Wired into a circuit with the motor-generator start switch that must be closed to put car I of a bank of elevators into operation is the coil of a relay 15. (In the drawing motor-generator start switch leads are labeled "To M. G. Start Switch I, II, III," etc.) When the coil of the relay 15 is energized, a contact 16 is opened and a contact 17 is closed.

Wired into a circuit with the motor-generator start switch that is closed to put car II into operation is a relay 18 which is connected to contacts 19, 20, 21 and 22. When the coil of the relay 18 is energized certain contacts 20 and 21 are closed and other contacts 19 and 22 are opened.

Wired into a circuit with the motor-generator start switch that is closed to put car III into operation is a relay 23 which is connected to contacts 24, 25, 26 and 27. When the coil of the relay 23 is energized certain contacts 25 and 26 are closed and other contacts 24 and 27 are opened.

Wired into a circuit with the motor-generator start switch that is closed to put car IV into operation is a relay 28 which is connected to contacts 29, 30, 31 and 32. When the coil of the relay 28 is energized certain contacts 30 and 31 are closed and other contacts 29 and 32 are opened.

Wired into the circuit with the motor-generator start switch that is closed to put car V into operation is a coil of a relay 33. When the coil of the relay 33 is energized, a contact 34 is opened and a contact 35 is closed.

When all the motor-generator start switches are closed and cars I, II, III, IV and V are in operation, current may pass through contacts 17, 21, 26, 31 and 35, as well as through the coil of the relay 14, which when energized closes the contact 12 and permits current to flow through the contact 11 whenever it is closed by the cam 6. Thus with the apparatus in the condition in which it is diagrammed, dispatch signals are sent alternately to the lower and upper terminals as the contacts 7 and 11 are closed alternately by the cams 4 and 6.

If the motor-generator start switch for car I is opened the coil of the relay 15 is deenergized, thus closing the contact 16 and opening the contact 17. With the contact 17 open and the contact 16 closed, current cannot flow through the relay 14 because the circuit which includes the contact 16 and the contacts 20, 25 and 30 also includes the contact 34 which is open. Hence when car I is taken out of service the relay 14 is deenergized, the contact 12 is opened and the contact 10 is closed. With the apparatus in this condition dispatch signals are sent simultaneously to the lower and upper terminals as the contacts 7 and 9 are closed simultaneously by the cams 4 and 5, and the relays 8 and 13 are simultaneously activated.

If instead of taking car I out of service, car II is taken out of service by opening its motor-generator start switch, the coil of the relay 18 is deenergized. This causes the contacts 20 and 21 to be opened and the contacts 19 and 22 to be closed. With the contact 21 opened and the contacts 17 and 19 closed the circuit which includes the contacts 17, 19, 25, 30 and 34 and

the coil of the relay 14 is open at the contact 34. Since the circuit is open the coil of the relay 14 is deenergized and dispatch signals are sent simultaneously to the lower and upper terminals just as they were when car I was taken out of operation.

Taking either car III or car IV out of service instead of car II likewise results in dispatch signals being sent simultaneously to the lower and upper terminals.

If only car V be taken out of service by opening its motor-generator start switch, the relay 33 will be deenergized and the circuit through the coil of the relay 14 will be broken at the contact 35. Current cannot pass through the contact 17 and the contact 35 as long as the contacts 19, 24 and 29 are open.

It is apparent from the foregoing explanation that taking any one of the five cars of the elevator bank out of service, and thus changing the number of cars left in operation to four, an even number, results in dispatch signals being sent simultaneously to the lower and upper terminals.

If while car I is out of service and consequently the contact 17 is open and the contact 16 is closed, car II also is taken out of service, leaving three cars, an odd number, in operation, current can flow through the contacts 16, 22, 26, 31 and 35 as well as through the coil of the relay 14, thus activating the relay and closing the contact 12 and opening the contact 19. With the contact 12 closed and the contact 19 opened, the relays 8 and 13 will be energized alternately as the contacts 7 and 11 are closed alternately by the cams 4 and 6. Hence with cars III, IV and V in operation, dispatch signals will be sent alternately to the lower and upper terminals. With cars I and III out of operation current will pass through the contacts 16, 26, 27, 31 and 35 as well as through the coil of the relay 14, so that signals will be sent alternately to the lower and upper terminals.

With cars I and IV out of service current will pass through the coil of the relay 14 and through the contacts 16, 20, 25, 32 and 35. With cars I and V out of service current will pass through the coil of the relay 14 and through the contacts 16, 20, 25, 30 and 34. With cars II and III out of service current will pass through the coil of the relay 14 and through the contacts 17, 19, 27, 31 and 35. With cars II and IV out of service current will pass through the coil of the relay 14 and through the contacts 17, 19, 25, 32 and 35. With any two cars out of service, leaving three cars, an odd number, in operation the coil of the relay 14 will be energized and dispatch signals will be sent alternately to the lower and upper terminals.

If three cars are taken out of service leaving two cars, an even number, in operation no current will pass through the coil of the relay 14. The contact 10, therefore, will be closed and the contact 12 open and signals will be sent simultaneously to the lower and upper terminals. If, for example, cars I, II and III are taken out of service, the circuit including the contacts 16, 22, 24 and 30 will be open at the contact 34 and no current will pass through the coil of the relay 14.

The instant invention has been shown as applied to a control system for a bank of five elevators, but it is equally applicable to banks of more or less than five elevators. It can be made applicable to a bank of four elevators by omitting one relay such as the relay 23 and its

contacts such as contacts 24, 25, 26 and 27 and cross connecting the contacts of the preceding and following groups. It can be made applicable to a group of six elevators by interposing another relay and group of contacts like the relay 23 with its group of contacts 24, 25, 26 and 27.

By incorporating the apparatus of the instant invention into a supervisory control system for a bank of elevators, the maintenance of balanced relationship between the cars serving up traffic and the cars serving down traffic is taken care of automatically, no matter how many cars are withdrawn from or restored to service.

Having described the invention, I claim:

1. Apparatus for automatically maintaining a balanced relationship between elevator cars serving up traffic and elevator cars serving down traffic, said apparatus comprising, in combination, means for sending dispatch signals at regular intervals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means controlled by switches employed to withdraw cars of such bank of elevators from service and to restore such cars to service which open and close said circuit as cars are withdrawn or restored, said circuit being so constructed and arranged that whether it is closed or open depends upon whether the number of cars in service is odd or even.

2. Apparatus for automatically maintaining a balanced relationship between elevator cars serving up traffic and elevator cars serving down traffic, said apparatus comprising, in combination, means for sending dispatch signals at regular intervals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means controlled by switches employed to withdraw cars of such bank of elevators from service and to restore such cars to service which open and close said circuit as cars are withdrawn or restored, said circuit being so constructed and arranged that whether it is closed or open depends upon whether the num-

ber of cars in service is odd or even, said means for automatically switching said simultaneously acting means into and out of action including a relay which is activated when said circuit is closed and deactivated when said circuit is open.

3. Apparatus for automatically maintaining a balanced relationship between elevator cars serving up traffic and elevator cars serving down traffic, said apparatus comprising, in combination, means for sending dispatch signals at regular intervals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means controlled by switches employed to withdraw cars of such bank of elevators from service and to restore such cars to service which open and close said circuit as cars are withdrawn or restored, said circuit being so constructed and arranged that whether it is closed or open depends upon whether the number of cars in service is odd or even, said means controlled by switches employed to withdraw cars from and restore cars to service including a plurality of relays and means whereby said relays open and close contacts in said circuit.

4. Apparatus for automatically maintaining a balanced relationship between elevator cars serving up traffic and elevator cars serving down traffic, said apparatus comprising, in combination, means for sending dispatch signals at regular intervals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means controlled by switches employed to withdraw cars of such bank of elevators from service and to restore such cars to service which open and close said circuit as cars are withdrawn or restored, said circuit being so constructed and arranged that whether it is closed or open depends upon whether the number of cars in service is odd or even, said means controlled by switches employed to withdraw cars from and restore cars to service including a plurality of relays and means whereby said relays open and close contacts in said circuit, each of said relays having a plu-

rality of contacts, each contact of each relay being wired in series with a pair of contacts of another relay, one of said pair of contacts being open and another of said pair of contacts being closed.

5. Apparatus for automatically maintaining a balanced relationship between elevator cars serving up traffic and elevator cars serving down traffic, said apparatus comprising, in combination, means for sending dispatch signals at regular intervals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means controlled by switches employed to withdraw cars of such bank of elevators from service and to restore such cars to service which open and close said circuit as cars are withdrawn or restored, said circuit being so constructed and arranged that whether it is closed or open depends upon whether the number of cars in service is odd or even, said means controlled by switches employed to withdraw cars from and restore cars to service including a plurality of relays, means whereby said relays open and close contacts in said circuit, said circuit offering alternative paths through the contacts of each relay, part of said paths passing through closed contacts whether said relay be activated or deactivated.

6. Apparatus for automatically maintaining a balanced relationship between elevator cars serving up traffic and elevator cars serving down traffic, said apparatus comprising, in combination, means for sending dispatch signals at regular intervals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means controlled by switches employed to withdraw cars of such bank of elevators from service and to restore such cars to service which open and close said circuit as cars are withdrawn or restored, said circuit being so constructed and arranged that whether it is closed or open depends upon whether the number of cars in service is odd or even, said means controlled by switches employed to with-

draw cars from and restore cars to service including a plurality of relays, means whereby said relays open and close contacts in said circuit, the two relays adjacent the ends of the circuit each having two contacts, the intermediate relays each having four contacts.

7. Apparatus for automatically maintaining a balanced relationship between elevator cars serving up traffic and elevator cars serving down traffic, said apparatus comprising, in combination, means for sending dispatch signals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means which open and close said circuit as cars are withdrawn from or restored to service, said circuit being so constructed and arranged that whether it is closed or open depends upon whether the number of cars in service is odd or even.

8. Apparatus for automatically maintaining a balanced relationship between elevator cars serving up traffic and elevator cars serving down traffic, said apparatus comprising, in combination, means for sending dispatch signals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means which open and close said circuit as cars are withdrawn from or restored to service, said circuit being so constructed and arranged that whether it is closed or open depends upon whether the number of cars in service is odd or even, said means for automatically switching said simultaneously acting means into and out of action including a relay which is activated when said circuit is closed and deactivated when said circuit is open.

9. Apparatus for automatically maintaining a balanced relationship between elevator cars serving up traffic and elevator cars serving down traffic, said apparatus comprising, in combination, means for sending dispatch signals to one terminal of a bank of elevators, simultaneously acting means for sending a dispatch signal to the other terminal of such bank of elevators each time a dispatch signal is sent to the one terminal,

alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means which open and close said circuit as cars are withdrawn from or restored to service, said circuit being so constructed and arranged that whether it is closed or open depends upon whether the number of cars in service is odd or even, said means controlled by switches employed to withdraw cars from and restore cars to service including a plurality of relays and means whereby said relays open and close contacts in said circuit.

10. Apparatus for automatically maintaining a balanced relationship between elevator cars serving up traffic and elevator cars serving down traffic, said apparatus comprising, in combination, means for sending dispatch signals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means into action, and means which open and close said circuit as cars are withdrawn from or restored to service, said circuit being so constructed and arranged that whether it is closed or open depends upon whether the number of cars in service is odd or even, said means controlled by switches employed to withdraw cars from and restore cars to service including a plurality of relays and means whereby said relays open and

close contacts in said circuit, each of said relays having a plurality of contacts, each contact of each relay being wired in series with a pair of contacts of another relay, one of said pair of contacts being open and another of said pair of contacts being closed.

11. Apparatus for automatically maintaining a balanced relationship between elevator cars serving up traffic and elevator cars serving down traffic, said apparatus comprising, in combination, means for sending dispatch signals to one terminal of a bank of elevators, simultaneously acting means for sending a dispatch signal to the other terminal of such bank of elevators each time a dispatch signal is sent to the one terminal, alternately acting means for sending dispatch signals to such other terminal at times intermediate the times when dispatch signals are sent to the one terminal, means for automatically switching said simultaneously acting means into or out of action and at the same time switching said alternately acting means out of or into action so as to implement either said simultaneously acting means or said alternately acting means, but not both of them at the same time, a circuit for selectively conditioning said means for automatically switching either said simultaneously acting means or said alternately acting means into action, and means which open and close said circuit as cars are withdrawn from or restored to service, said circuit being so constructed and arranged that whether it is closed or open depends upon whether the number of cars in service is odd or even, said means controlled by switches employed to withdraw cars from and restore cars to service including a plurality of relays for means whereby said relays open and close contacts in said circuit, said circuit offering alternative paths through the contacts of each relay, part of said paths passing through closed contacts whether said relay be activated or deactivated.
